United States Patent Office.

ISAAC P. WENDELL, OF PHILADELPHIA, PENNSYLVANIA, ASSIGNOR TO EBERT J. WENDELL, OF SAME PLACE.

Letters Patent No. 84,326, dated November 24, 1868; antedated May 25, 1868.

IMPROVED JOURNAL-BEARING FOR RAILROAD-CARS.

The Schedule referred to in these Letters Patent and making part of the same.

To all whom it may concern:

Be it known that I, ISAAC P. WENDELL, of the city and county of Philadelphia, and State of Pennsylvania, have invented a new and improved Journal-Bearing for Railroad-Cars; and I do hereby declare that the following is a full and exact description thereof, reference being had to the accompanying drawings, and to the letters of reference marked thereon.

The nature of my invention consists of journal-bearings for railroad-cars, connected with an oil-chamber, and openings leading therefrom to the concave surface of the bearing, and supplying the journal with oil by means of capillary attraction, as hereinafter described.

In the accompanying drawings, which make a part of this specification—

Figure 1 is a plan or top view of the improved bearing.

Figure 2 is a vertical longitudinal section of the same.

Figure 3 is a cross-section.

Figure 4 is a horizontal section at the line $x x$.

Like letters in all the figures indicate the same parts.

A is the improved bearing, whose upper surface is made of such form as to conform to the surface of the journal-box.

The piece is cast with a chamber, B, to contain the oil for lubricating the journal.

The requisite strength of the bearing is preserved by making its central part solid, as represented in the drawings. Other solid parts in the area of the oil-reservoir may be made without decreasing too much the capacity of the chamber.

There are tubes or openings, C, which extend from the wearing or concave surface, a, of the bearing to the upper part of the chamber.

I place cotton or woollen cords, D, or other suitable material, in the chamber B, and extend them through

the tubes C. I then fill the chamber with oil, and cover the openings b, by turning the covers E over them. These covers should be even with the upper surface of the bearing, so that the latter may fit against the under surface of the top of the box, or intermediate wedge. Instead of turning on a centre, the covers may slide into place between dovetails, or be made to drop into the openings.

An extension may be made at one end of the bearing, for filling it with oil, and without removing the bearing.

It will readily appear that the oil will be carried to the journal by capillary attraction through the cord D, so as to supply the journal with oil in a very even manner, no more passing through it than is necessary for the lubrication, in consequence of the journal being always against the face of the bearing, the cord, which fills the tubes C, being sufficiently tight to prevent a too rapid flow of oil.

I do not claim, broadly, oil-chambers and tubes, or the porous cords above the bearings of axles, as such have been known and used before; but

What I claim as new, and desire to secure by Letters Patent, is—

The journal-bearing A, constructed with an oil-chamber, B, and tubes or openings, C, which are provided with a cord, D, or other fibrous material, substantially in the manner and for the purpose set forth.

In testimony that the above is my invention, I have hereunto set my hand and affixed my seal, this 2d day of March, 1868.

ISAAC P. WENDELL. [L. S.]
